US00D783480S

(12) **United States Design Patent** (10) **Patent No.:** **US D783,480 S**
(45) **Date of Patent:** **** Apr. 11, 2017**

(54) **REARVIEW DEVICE**

(71) Applicant: **Gentex Corporation**, Zeeland, MI (US)

(72) Inventors: **Eric S. Sloterbeek**, Hudsonville, MI (US); **Danny L. Minikey, Jr.**, Fenwick, MI (US); **Bradley R. Hamlin**, Allendale, MI (US)

(73) Assignee: **GENTEX CORPORATION**, Zeeland, MI (US)

(**) Term: **15 Years**

(21) Appl. No.: **29/550,127**

(22) Filed: **Dec. 30, 2015**

Related U.S. Application Data

(62) Division of application No. 29/511,063, filed on Dec. 5, 2014, now Pat. No. Des. 746,744.

(51) **LOC (10) Cl.** **12-16**

(52) **U.S. Cl.**

USPC **D12/187**

CLAIM

We claim the ornamental design for a rearview device, as shown and described.

DESCRIPTION

FIG. 1 is a top front perspective view of a rearview device of the present disclosure;

FIG. 2 is a bottom front perspective view of the rearview device of FIG. 1;

FIG. 3 is a front elevational view of the rearview device of FIG. 1;

FIG. 4 is a rear elevational view of the rearview device of FIG. 1;

FIG. 5 is a top plan view of the rearview device of FIG. 1; FIG. 6 is a bottom plan elevational view of the rearview device of FIG. 1;

FIG. 7 is a first side elevational view of the rearview device of FIG. 1; and,

FIG. 8 is a second side elevational view of the rearview device of FIG. 1.

The broken lines depict portions of the article that form no part of the claimed design.

1 Claim, 5 Drawing Sheets
